United States Patent Office

Des. 177,592
Patented May 1, 1956

177,592

BATH TUB

Clarence J. Rodman, Alliance, Ohio, assignor, by mesne assignments, to AllianceWare, Inc., a corporation of Delaware

Application February 17, 1955, Serial No. 34,563

Term of patent 14 years

(Cl. D4—4)

FIG. 1

The characteristic features of the design are shown in solid lines.

I claim:

The ornamental design for a bath tub, as shown and described.
